UNITED STATES PATENT OFFICE.

GLENN MORE, OF JAMESTOWN, NEW YORK, ASSIGNOR TO THE BLACKSTONE MANUFACTURING COMPANY, OF JAMESTOWN, NEW YORK, A CORPORATION OF NEW YORK.

OPERATING-GEARING FOR WASHING-MACHINES.

1,220,767.

Specification of Letters Patent. Patented Mar. 27, 1917.

Application filed May 22, 1916. Serial No. 99,051.

To all whom it may concern:

Be it known that I, GLENN MORE, a citizen of the United States, and a resident of Jamestown, in the county of Chautauqua 5 and State of New York, have invented certain new and useful Improvements in Operating-Gearing for Washing-Machines; and I do hereby declare that the following is a full, clear, and exact description there- 10 of, reference being had to the accompanying drawings, and to the letters of reference marked thereon, which form a part of this specification.

This invention relates to improvements in 15 operating mechanism for washing machines and the like and consists of the matters hereinafter described and more particularly pointed out in the appended claims.

One object of my invention is to provide 20 a simple, effective device in which a part of the operating mechanism is mounted upon a fixed support and another part upon a movable support but in which the two sets of mechanisms are constantly in operative con- 25 nection, whereby the movable support may be moved from its normal position or retained operatively therein, without the necessity of connecting or disconnecting any of the operative elements of the mechanism.

Another object of the invention is to provide 30 a mechanism wherein when the prime mover is actuated manually, the force of the power exerted by the operator is applied with substantial directness to the operating shaft and also is materially assisted by a 35 high speeded fly wheel operatively connected to said prime mover.

These objects and the many advantages 40 of my improved operating mechanism will appear as I proceed with my specification.

In the drawings:

Figure 1 represents a view in side elevation of a washing machine provided with my improved operating mechanism.

Fig. 2 represents a top plan view thereof.

Fig. 3 represents a view similar to that shown in Fig. 1 but with the parts in a changed relation.

Figs. 4 and 5 represent detail sectional 50 views on an enlarged scale, through parts of my improved operating mechanism, the planes of said sections being indicated by the lines 4-4 and 5-5 respectively of Fig. 2.

Referring now to that embodiment of my

invention illustrated in the accompanying drawings, 10 indicates the tub body of a washing machine which is mounted upon upright supporting legs 11 in the familiar manner. The tub body 10 has a stationary 60 top wall 12 to which a lid 13 is hinged along one edge 13^a as hereinafter described. Said stationary top wall 12 and lid 13 in this case provide supports for the operating mechanism. 65

14 indicates an upright, vertically reciprocating beater shaft which projects through the tub lid 13. Said shaft is arranged, preferably, coaxially with respect to the tub body 10 and has a beater head 15 70 fixed to that end within the tub body. The shaft 14 has sliding bearing in a sleeve 16 which projects through a suitable aperture in the tub lid 13, and said sleeve is made integral with a bracket plate 17 fixed to and 75 supported upon the top surface of said lid. The opposite or top end of said beater shaft 14 has fixed to it, a collar 18, to which is operatively connected the means for imparting a vertical reciprocating movement 80 to said shaft.

The bracket plate 17 extends toward that edge 13^a of the lid which engages the stationary top wall 12 of the tub body. Adjacent said edge, said bracket 17 is 85 provided with upright spaced standards 19-19^a which have laterally extending arms 20-20^a, normally horizontal, adapted for hinged connection with upright standards 21-21^a made integral with a bracket casting or plate 22 fixed to and supported upon the stationary top wall 12 of the tub body. 90

23 indicates a horizontally disposed shaft which is fixed at its ends in suitable apertures formed in the top ends of the upright standards 19-19 of the bracket plate 17, said shaft being arranged parallel with the edge 13^a of the lid 13. Loosely mounted in said shaft, so as to rock thereon, is a bell crank-prime mover-lever, indicated as a 100 whole by the numeral 24.

The prime mover or lever 24 has an arm 25, disposed in a substantially horizontal direction, which extends into the vicinity of the beater or operating shaft 14. The end 25^a of said arm is preferably forked and operatively connected to the collar 18 at the top end of said beater shaft. Said prime mover or lever 24 also includes a substantially upright or vertically arranged 105 110

socket member 26 adapted to receive one end of a hand bar 27. Said prime mover or lever is also provided with a short arm 28, which extends in substantial parallelism 5 to the arm 25 in a plane adjacent the upright standard 19.

The upright standards 21—21^a of the bracket casting or plate 22 are provided at their top ends, respectively, with axially arranged studs 21^b—21^c, extending parallel with the shaft 23 before mentioned. The outer ends of the horizontal arms 20—20^a of the bracket plate 17 are provided with suitable bearing apertures to engage said 10 studs 21^b and 21^c, thereby providing a hinged connection between said movable support or lid 13 and the stationary support or top wall 12. Rotatively mounted on one of the studs (in this instance, the stud 21^b), is a spur gear 32 of comparatively 15 large diameter (see Fig. 4), which gear meshes with a smaller bevel gear 33 fixed to the inner end of a shaft 34. Said shaft 34 is journaled in a bearing sleeve 35 made 20 integral with the bracket casting 22. It will be observed that said shaft 34 and its associated bearing sleeve are positioned adjacent to the proximate edges of the supports 12 and 13, and that the axis of said 25 shaft 34 is parallel with the edge 13^a of the lid or support 13. A fly wheel 36 is fixed upon the outer end of the shaft 34, beyond the bearing sleeve 35.

The gear 32 has a crank pin 37 which is 30 operatively connected by means of a link or pitman 38, to the arm 28 of the prime mover or lever 24, whereby said gear is caused to rotate by the oscillating movement of the lever arm 28.

Made integral with the upright bearing 35 arm 21^a of the bracket 22 is a stop lug or shoulder 39. This shoulder 39 is adapted to be engaged by a coating lug or shoulder 40 formed on the horizontal arm 20^a of the 40 bracket plate 17 (see Figs. 2 and 4). When the movable support or lid 13 is swung about the studs 21^b—21^c of the bracket plate 22 into the desired open or substantially vertical position, the shoulder 40 on the arm 45 20^a will engage upon the shoulder 39 on the upright arm 21^a and thus prevent the lid from being further moved in that direction and also support it in the desired open position. A gear cover or guard 41 is fixed 50 in position upon the upright bearing arm 21^a of the bracket 22 in a manner to protect the gears 32—33 against breakage and also against accidental engagement of the person or clothing of the operator.

The operation of my improved operating 55 mechanism is as follows:

With the clothing or other garments in the tub body, the tub lid 13 is locked in its closed position in the usual manner. The 60 operator next grasps the handle 27 of the

prime mover lever and imparts a back and forth rocking movement thereto about the shaft 23 as an axis. Through the operative connections before mentioned, the horizontal arm 25 will impart a vertically reciprocating movement to said shaft, and the beater 15 fixed to the lower end of said shaft will operate to clean the clothing within said tub. On account of the connection afforded by the link 38 between the 70 arm 28 of said prime mover lever and the crank pin 37 on the large gear 32, said gear will be continuously rotated in one direction and this rotative motion will be transmitted to the small gear 33 on the fly 75 wheel shaft 34 at a considerably higher speed. 80

When under way, the momentum of the fly wheel 36 will materially assist in the operation of the mechanism so that the 85 effort expended by the operator to impart the proper movement to the prime mover lever 24 is greatly lessened.

When it is desired to gain access to the interior of the tub for any purpose, the lid is first unlocked. It may now be swung from its horizontal or closed position, about the studs 21^b—21^c, as an axis, into an open, substantially vertical position, and held in said position by reason of the engagement 90 of the lugs 39 and 40 before mentioned. 95

My improved operating mechanism possesses many advantages, one of which is that but a small portion of said mechanism is mounted on the movable support or lid, thus making it possible to open said lid but with little effort on the part of the operator. As will be apparent, the heavier parts of the mechanism are mounted on the stationary support or top of the tub. This 100 relieves the lid from the great stress and strain when the device is being operated and also affords a little better balance to the whole device as a unitary portable structure. 105

Another advantage is that, accidental closing of the lid 13 when the same is in an open position, is impossible as the greater part of the weight of the mechanism carried thereby is located in a plane back of the vertical plane of said lugs 21^b—21^c which forms the pintle of the hinge connection between the stationary top 12 of the tub and the lid 13. This follows from the relative location of the lugs 39 and 40 115 when engaged, as compared with the location of the axis of pins 21^b and 21^c. 120

It is obvious that instead of applying operative manual power to my device through the hand bar 27 and the lever 24, 125 power may be applied through the shaft 34 either by placing a driving belt upon the fly wheel 36 or by placing a belt pulley or other driving member upon the outer end of said shaft 34 in a familiar manner. 130

While in describing my invention, I have referred to certain details of mechanical construction and arrangement of parts, I do not wish to be limited thereto except as 5 may be pointed out in the appended claims.

I claim as my invention:

1. The combination of a support and an auxiliary support, a bracket plate on said support, a second bracket plate on said 10 auxiliary support, means operatively connecting said bracket plates providing a hinged connection between said supports, an operating shaft journaled in the bracket on said auxiliary support, a fly-wheel shaft, a fly-wheel and a large gear wheel all carried by the bracket plate on said main support, said gear being arranged with its axis of rotation coincident with the axis of the 15 hinged connection between said supports and being operatively engaged with said fly-wheel shaft, a rocking lever carried on said auxiliary support, and directly connected to the operating shaft and means 20 operatively connecting said lever to said gear for imparting a continuous rotary movement to said large gear and a like movement to said fly-wheel at high speed.

2. The combination of a fixed support and a movable support, a bracket plate on 30 said fixed support, a second bracket plate on said movable support, means operatively connecting said bracket plates providing a hinged connection between said supports, an operating shaft capable of a vertical, 35 reciprocating movement journaled in the bracket on said movable support, a fly-wheel shaft carried by the bracket plate on said fixed support, a rocking prime mover lever journaled on one of said bracket 40 plates, said lever being directly connected to and imparting a vertical reciprocating movement to said operating shaft and means operatively connecting said prime mover lever to said fly-wheel shaft, to impart a continuous rotary movement thereto, said means 45 including a high speed gearing.

3. The combination of a main or fixed support and an auxiliary or movable support, a bracket plate on each support, means 50 operatively connecting said bracket plates providing a hinged connection between said supports, an operating shaft, journaled in the bracket on the movable support, a fly-wheel shaft and a fly-wheel thereon carried 55 by the bracket plate on said fixed support, a large gear arranged with its axis of rotation coincident with the axis of the hinged connection between said supports and operatively connected to said fly-wheel shaft, a lever mounted on the bracket plate on the 60 movable support, said lever including a plurality of load arms one of which arms is directly connected to the operating shaft and the other arm indirectly connected to 65 said large gear, said lever through its con-

nections imparting a vertical reciprocatory movement to said operating shaft and a continuous rotary movement to said large gear.

4. The combination of a main support 70 and an auxiliary support connected thereto, a bracket plate having upright bearing standards fixed to said main support, a second bracket plate fixed to said auxiliary support, said second bracket plate having 75 laterally extending arms adapted for pivotal engagement with the upright standards on the first named bracket plate to provide a hinged connection between said main and auxiliary supports, a continuous 80 rotary fly-wheel shaft and associated gearing carried by the bracket plate on said main support, an upright, vertical reciprocatory operating shaft having sliding bearing in the bracket plate on said auxiliary 85 support, a rocking lever carried by one of said plates directly connected to said operating shaft and means operatively connecting the associated gearing of the fly-wheel shaft with said operating lever, said means 90 being constructed to translate the rocking movement of said lever into a continuous rotary motion of the fly-wheel shaft gearing.

5. The combination of a support and an auxiliary support hinged thereto, a bracket 95 plate fixed to said first support, a fly-wheel shaft and a gear for driving the same at high speed mounted on said bracket, a second bracket fixed to said auxiliary support, said bracket plates having parts pivotally 100 connected together and forming the hinged connection between said main and said auxiliary supports, an operating shaft journaled in said bracket on said auxiliary support, a rocking lever mounted on said last 105 mentioned bracket and having an arm directly connected with the operating shaft and means connecting said lever with the said driving gear, said means translating the rocking movement of said lever into a 110 continuously rotary movement of said gear and to said fly-wheel shaft at high speed.

6. The combination of a main support and an auxiliary support, a bracket plate fixed to said main support and having upright bearing standards provided with alined bearing studs, a second bracket plate fixed to said auxiliary support and having laterally extending arms adapted for pivotal engagement with the alined studs of the 120 first mentioned bracket plate whereby a hinged connection between said main and auxiliary supports is provided, a fly-wheel shaft carried by the first mentioned bracket plate, a gear on said shaft, a comparatively 125 large gear journaled on the studs of one of said upright bearing standards, a vertically reciprocating operating shaft journaled in the bracket plate on said auxiliary support, a rocking lever having a load arm with a 130

forked free end engaging with the operating shaft, a second load arm depending below the first mentioned arm, and a link operatively connecting the second or lower load arm with the said large gear.

7. The combination of a main support and an auxiliary support, a bracket plate fixed to said main support and having upright bearing standards provided with alined bearing studs, a second bracket plate fixed to the auxiliary support, said second bracket plate including upright standards having laterally projecting arms adapted for pivotal engagement with the alined studs of the first named bracket plate whereby a hinged connection between said main and auxiliary supports is provided, a continuous rotary shaft journaled on said first named bracket, a fly-wheel fixed to one end of said shaft, a spur pinion fixed to the other end of said shaft, a comparatively large gear journaled on the stud of one of said upright standards on the first mentioned bracket plate, a vertically reciprocating operating shaft journaled in the bracket plate on said auxiliary support, a rocking lever journaled in the top end of the standards on said bracket plate, said lever having a load arm operatively connected with said operating shaft, a second load arm depending below said first mentioned arm, and a link operatively connecting said depending arm with the large gear.

8. The combination of a main support and an auxiliary support connected thereto and capable of being moved from the plane of said main support about an axis into a position substantially at right angles thereto, a bracket plate having upright bearing standards fixed to said main support, said bearing standards having alined bearing studs, a second bracket plate fixed to said auxiliary support, said bracket plate having upright

bearing standards provided with laterally extending arms adapted for pivotal engagement with the alined studs of the first named bracket plate to provide the hinged connection between said main and auxiliary supports, a fly-wheel shaft carried by the first named bracket plate, a gear pinion on one end of said shaft, a comparatively large gear journaled on the stud of one of said upright bearing standards on said last mentioned bracket plate and meshing with the gear on the fly-wheel shaft, an operating shaft capable of vertical reciprocatory movement journaled in the bracket plate on said auxiliary support, a rocking hand lever journaled in the top ends of the upright standards on the last mentioned bracket plate, said lever having load arms, one of which has a forked end engaging the top end of said operating shaft, a crank pin on said large gear, a link connecting the other load arm of said lever with said crank pin, a gear cover mounted on that bearing standard carrying said large gear, said cover inclosing said large gear and the gear on the fly-wheel shaft, a shoulder made integral with said last mentioned standard and a second shoulder made integral with the associated laterally extending arm of the bracket plate on said auxiliary support, said shoulders engaging each other when said auxiliary support is swung about its pivot into a substantially vertical position and limiting the movement of said auxiliary support relative to the main support.

In testimony, that I claim the foregoing as my invention I affix my signature in the presence of two witnesses, this 2nd day of May, A. D. 1916.

GLENN MORE.
